UNITED STATES PATENT OFFICE.

WALTER C. DYER, OF CHICAGO, ILLINOIS, ASSIGNOR TO THE BUDA COMPANY, A CORPORATION OF ILLINOIS.

DRILLING-MACHINE.

1,376,084.

Specification of Letters Patent. Patented Apr. 26, 1921.

Application filed January 23, 1919. Serial No. 272,619.

To all whom it may concern:

Be it known that I, WALTER C. DYER, a citizen of the United States, residing at Chicago, county of Cook, and State of Illinois, have invented certain new and useful Improvements in Drilling-Machines, of which the following is a specification.

This invention relates in general to drilling apparatus, and is an improvement upon 10 that type of drill adapted for drilling bond wire or other holes in railroad rails, such as described in the United States Letters Patent to Place and Jenkins No. 1,175,556, and to myself, No. 1,221,708, of April 3, 1917. 15 My invention has for one of its primary objects the provision of novel means for clamping the drill to the rail, whereby the drill may be readily accommodated to the different sizes of rails commercially used, 20 irrespective of variations both in width and depth of the head of the rail.

My invention also contemplates a drill having the characteristics set forth which is supported in operative drilling position 25 against the rail, independently of the ground.

In addition, my invention consists in the provision of a clamping device which will engage the rail at a plurality of points, the 30 movable rail engaging parts being operated by a common operating means.

The foregoing, together with such other objects as may hereinafter appear or are incident to my invention, I attain by means 35 of an improved construction illustrated in preferred form in the accompanying drawings, wherein:

Figure 1 is a vertical sectional view of a drill embodying my improvements, the 40 drill being shown in operative drilling position; Fig. 2 is a horizontal section taken on the line II-II of Fig. 1; Fig. 3 is a fragmentary section taken on the line III-III of Fig. 1.

Referring now to the drawings, the drill 45 comprises a base frame 6 in which the spindle 8 with its bit 9 are mounted for rotative and for longitudinal movement with reference to the rail 10^a; an upper frame portion 10 extending upwardly from the base, in which is mounted the crank shaft 11 carrying the usual sprockets 12 and 13 and the crank 14, the sprockets being operatively connected to the spindle by means of the 50 drive chains 15 and 16 respectively engag-

ing the sprockets 17 and 18; and the clamping device indicated as a whole at A.

In so far as the drill proper is concerned, it will be sufficient to say that by the mechanism described, the drill 9 is simultaneously 60 advanced and rotated in a manner well-known in this art.

Referring now to the clamping and drill supporting mechanism A, it will be seen that this device comprises a pair of complementary side frame members 19 having rearwardly extending arms 20, adapted to be bolted to the frame parts of the drill proper. Each side frame member is provided with a rectangular slot 21, in each of 70 which a bearing block 22 is slidably mounted, the position of the bearing blocks being adjusted by means of the wing screws 23 and lock nuts 24. Rotatably mounted in the bearing blocks is a shaft 25, such shaft 75 being provided with three eccentrics 26, 27 and 28, preferably formed integrally with the shaft. The shaft is rotated by means of the lever 29.

A second shaft 30 is also mounted in the 80 side frame members in such manner that the dogs 31, preferably formed integrally therewith, will be engaged by the eccentrics 26 and 27, by means of which, when the shaft 25 is rotated through the medium of the 85 lever 29, the dogs 31 will be forced into tight engagement with the lower near corner of the head of the rail which is to be drilled, in the manner illustrated in Fig. 1.

The side frame members also have mounted therein a shaft 32 which carries a hook member B, the inner end of said hook member being adapted to engage the eccentric 28 in such manner that when the shaft 25 is rotated in the direction of the arrow, the inner end of the hook B is elevated and the outer end is depressed. The outer end of the hook B carries a block 33, adjustment of which is effected by the wing nut 34. The block 33 has a nose 35 engaging under 100 the lower outer corner of the head of the rail. The downward and inward movement of the outer end of the hook imparted by the eccentric 28 brings the block 33 and nose 35 in position to tightly engage the 105 lower far corner of the head.

In applying the drill, the block 33 is first adjusted to suit the depth of head and the journals for the eccentric or cam shaft are adjusted to suit the width of the head. With 110

the operating lever in the up position, the dogs 31 and the block 33 will be held by gravity in substantially vertical positions so that the side arm members of the drill 5 may be readily placed on the rail, with the dogs and the block straddling the rail. The operating lever is now pushed downwardly to rotate the eccentric shaft, simultaneously jamming the block 33 under the far lower 10 corner of the head and the dogs 31 under the near lower corner. The axis of rotation of the hook member is nearer the outer end of the hook so that normally when the operating lever is in up position the inner end 15 will bring the outer end into a substantially vertical position by the action of gravity.

From the foregoing it will be seen that when the drill is positioned, the side frame members rest upon the top of the head, and 20 the dogs 31 and block 33 engage the lower opposite corners of the head. The drill thus has a two point support on top and a three point support on the bottom of the head. The drill is, in this manner, firmly supported by the rail itself, independently of 25 the ground, for the drilling operation. It will also be apparent that the clamping device will accommodate itself to differences in width of head, by virtue of the fact that 30 the axis of the shaft 25 can be quickly shifted by means of the wing screws 23. The dogs 31 are of such construction that they inherently accommodate themselves to differences in depth of head, while the adjustable 35 mounting of the block 33 is such that it may also be readily accommodated to differences in depth of head.

I claim:—

- 40 1. In a rail drilling machine, the combination of a frame, an outer rail gripping element pivoted to the frame, an inner rail gripping element pivoted to said frame, and a common means for operating said gripping elements, both of said elements being adapted to be held by gravity away from the rail when not operated on to grip the rail.
- 45 2. In a rail drilling machine, the combina-

tion of a frame, an outer rail gripping element pivoted to said frame, an inner rail gripping element pivoted to said frame, a 50 shaft mounted in said frame, and eccentric means carried in said shaft for operating said rail gripping elements, both of said gripping elements being maintained by gravity away from the rail when not operated on 55 to grip the rail.

3. In a rail drilling machine, the combination of a frame, an inner rail gripping element pivoted to the frame, a pivotally mounted hook constituting an outer rail 60 gripping element, camming members adapted to operate said rail gripping elements, and a shaft for operating said cams, the inner rail gripping element and the hook being maintained by gravity away from the rail 65 when not operated on to grip the rail.

4. In a rail drilling machine, the combination of a frame adapted to rest upon the rail, an outer rail gripping element pivoted on said frame above the rail and having an 70 end extending inwardly across the rail, an inner rail gripping element pivoted on the frame, and a common means for operating both of said gripping elements from the inside of the rail. 75

5. In a rail drilling machine, the combination of a frame, outer rail gripping means pivotally mounted on the frame, inner rail gripping means pivotally mounted on the frame and independent of said outer gripping means, and a common means for operating both of said gripping means. 80

6. In a rail drilling machine, the combination of a frame, outer rail gripping means pivotally mounted for swinging movement 85 on said frame, inner rail gripping means pivotally mounted for swinging movement on said frame, and means for operating the gripping means, both of said gripping means being adapted to swing away from the rail 90 when not operated on to grip the rail.

In testimony whereof I have hereunto signed my name.

WALTER C. DYER.
